CANDLE WARMER OR THE LIKE

Ronald G. DePuy, Corning, N.Y., assignor to Corning Glass Works, Corning, N.Y.

Filed July 30, 1970, Ser. No. 24,223

Term of patent 14 years

Int. Cl. D7—02

U.S. Cl. D44—10

Fig. 1

Fig. 2

Fig. 3

Fig. 4

FIG. 1 is a top plan view of a candle warmer or the like embodying my new design.

FIG. 2 is a front elevational view, with the rear and side elevational views being identical.

FIG. 3 is a cross sectional view in elevation taken along line 3-3 of FIG. 1.

FIG. 4 is an elevational view in section taken along line 4-4 of FIG. 1.

I claim:

The ornamental design for a candle warmer or the like, as shown and described.
